United States Patent Office.

EDWARD HEWETT, OF ST. LEONARD'S-ON-SEA, ENGLAND.

Letters Patent No. 96,430, dated November 2, 1869.

CHIMNEY-COWL.

The Schedule referred to in these Letters Patent and making part of the same.

To all whom it may concern:

Be it known that I, EDWARD HEWETT, of St. Leonard's-on-Sea, in the county of Sussex, England, have invented a new and useful Improvement in Cowl for Chimneys and Shafts: and I do hereby declare that the following is a full, clear, and exact description thereof, which will enable those skilled in the art to make and use the same, reference being had to the accompanying drawings, forming part of this specification.

My invention relates to improvements in the construction of cowls, to be applied to chimneys and furnace-shafts, whereby an efficient up-draught is obtained and down-draught at the same time is prevented.

According to my invention, I form the cowl of a tube of considerable height, and of about the same diameter as the chimney itself, above which it is mounted, so as to turn on a vertical pivot, fastened to the chimney.

The top of this tube may either be closed, and provided with an aperture at one side for the exit of the smoke, or it may be of curved form, like an ordinary cowl, and in each case provided with a suitable vane.

The top of the chimney is provided with an annular inclined plane for the support of the cowl, near the lower end of the cowl, and at the opposite side of the exit-opening above mentioned is a funnel-shaped opening for the admission of air, which (as the opening is always kept facing the wind by the action of the vane at top) rashes in and passes up the annular space surrounding an inner smoke-tube, and out at the top of the cowl.

The air, in passing out of the cowl, carries the smoke with it, thus creating a strong upward draught in the chimney.

A modification of this arrangement consists in dispensing with the central smoke-tube, and providing the revolving cowl with a longitudinal diaphragm extending about half way up the same.

The cowl is thus divided into two parts, one of which is open to the chimney for the passage of the smoke, and the other communicating, as before, with the outer air, admits a strong upward current of air through the cowl, which carries the smoke with it, and produces the draught desired.

In each case I prefer that the volume of air admitted through the cowl should be at least equal to the volume of smoke escaping at the top of the chimney.

These cowls are applicable to most kilns of similar structure, and to air-shafts for ventilating-purposes; also for raising gases and vapors which are either lighter or heavier than atmospheric air.

Figure 1 represents a side elevation of one arrangement of cowl of my invention;

Figure 2 is a vertical section of the same, showing the internal arrangement;

Figure 3 is a side view of a modification of the same:

Figure 4, a vertical section of said modification; and

Figure 5, an end view of the same.

Similar letters of reference indicate corresponding parts.

A is the tube forming the cowl, mounted above the chimney-top B on a vertical rod, C, fixed to the chimney-top B, on which the cowl turns on a pivot.

The upper end of the tube A is closed, and an aperture D is provided on one side for the exit of the smoke.

The upper part of the cowl may be of curved form, like an ordinary cowl, in any case being provided with a suitable vane or vanes, E.

Within the tube of the cowl is arranged a central smoke-tube, F, of about half the diameter of A.

The top of the tube F is diverted into the same direction with the upper part D, of A, as seen in fig. 2.

At the lower part of the cowl, and at the opposite side of the exit-opening D, above mentioned, is, in the pipe A, an opening, G, for the admission of air, to facilitate which, the opening G may further be provided with a funnel-shaped mouth, if desired.

As this opening G is always kept facing the wind, by the action of the latter on the vanes E, the air entering the cowl passes up the annular space H, contained between the smoke-tube F and the outer tube A of the cowl, and out at the exit-tube D at the top of the cowl, creating a strong upward draught in the chimney, for extracting the smoke contained.

In order to prevent the cowl from being carried away by the wind, and at the same time to allow perfect freedom in turning, I provide the cowl with the central tube I, as seen; which surrounds the pivot C throughout the greater part of its length, thereby preventing the removal of the cowl by the wind.

J J' are flanges formed around the base of the cowl and the top of chimney B respectively, to prevent the admission of the wind or rain, and to form as nearly as possible an air-tight joint.

The arrows show the direction of the smoke, and the dotted arrows that of the air-current.

The tube F may form part of the cowl, as shown, or it may project from the chimney into the cowl, in which case the bent upper part must be dispensed with.

The central smoke-tube F may be entirely dispensed with, and an inclined diaphragm in the lower part of the tube A, substituted therefor.

This diaphragm may only be carried about half way up the cowl, but I prefer to carry it entirely up.

The lower part of the cowl is thus divided into two parts, the one of which is open to the chimney B, for the passage of the smoke, as seen, and the other, communicating, as before, with the outer air, admits a strong upward current of air through the cowl, which carries the smoke with it, and produces the up-draught desired.

According to another arrangement illustrated in figs. 3, 4, and 5, I mount the cowl A' at an angle to chimney B, instead of being in line therewith, as before.

The smoke-tube F, to which the cowl is fastened, passes first upward perpendicularly and is then carried at the same angle as the cowl A', in which it occupies a central position, as seen.

By this arrangement the smoke is diverted from its perpendicular course into a line with the constant current of air passing through the annular space H before coming in contact therewith.

A funnel may in this case also be formed at the lower end of the cowl, to facilitate the entrance of the air which passes through the annular space H, and mixing with the smoke before it leaves the cowl, creates a strong upward current in the chimney.

The smoke-tube F is in this way supported in the chimney in the same manner in which the cowl is held in fig. 2.

An inclined diaphragm placed in the inclined cowl, may be substituted for the smoke-tube F, and would be so placed as to deflect the smoke on entering the cowl; a second diaphragm serving to close up one

half of the chimney-aperture, and cause the smoke, on issuing therefrom, to pass between the two diaphragms in an inclined upward direction.

The air passes through the cowl above the first diaphragm, also in an upward direction; by reason of its slanting position, and catching the smoke before leaving the cowl, creates the draught required.

In order to prevent an accumulation of soot in the several smoke-tubes F, which are inaccessible to the brushes or cleaning-devices, one or more balls of cork or other suitable material may be placed in said tubes, the balls being retained therein by wire netting placed at the top and bottom of the tube. These balls are maintained continually in motion by the current of air created in the tube, thereby preventing the soot from lodging therein.

The tubes composing the improved cowls, of my invention, may either be cylindrical, as shown, or in the form of truncated cones, or of other shape.

Having thus described my invention,

What I claim as new, and desire to secure by Letters Patent is—

1. A chimney-cowl, provided with an air-tube and smoke-pipe, whose outlets are nearly in the same vertical plane, as shown and described.

2. A chimney-cowl, provided with the tube I, to preserve it in its exact vertical position, as set forth.

3. A smoke-tube, provided with a base, attached to the chimney by two intermediate bevelled flanges, J J, to make a tight joint, as set forth.

The above specification of my invention signed by me, this day of May, 1869.

EDD. HEWETT.
